UNITED STATES PATENT OFFICE.

JAMES B. OLIVER, OF SHIELD'S STATION, PENNSYLVANIA.

CROSS-BAR FOR TELEGRAPH-POLES.

SPECIFICATION forming part of Letters Patent No. 540,799, dated June 11, 1895.

Application filed August 10, 1894. Serial No. 519,952. (No model.)

To all whom it may concern:

Be it known that I, JAMES B. OLIVER, of 5
Shield's Station, in the county of Allegheny
and State of Pennsylvania, have invented a
new and useful Improvement in Cross-Bars
for Telegraph-Poles, of which the following is
a full, clear, and exact description, reference
being had to the accompanying drawings,
forming part of this specification, in which—

10 Figure 1 is a front elevation of a telegraph-
pole provided with my improved cross-bar.
Fig. 2 is a side elevation of the same; and Fig.
3 is a cross-section on the line III III of Fig. 1,
with the cross-arm partly broken away.

15 My invention relates to the cross-arms used
upon telegraph poles for the attachment of
the insulators, and is designed to provide a
metal arm which shall take the place of the
wooden arms now employed, and an improved
20 connection for the arm and the pole.

In the drawings, 2 represents a portion of
a telegraph pole, having a cross-arm 3, com-
posed of an angle-iron, whose horizontal flange
4 is inserted within a horizontal slot formed
25 in the side of the pole. This cross-arm is per-
forated for the insertion of screw-bolts 5, which
pass through the web into the post and secure
the arm in place. As additional means for
securing the arm in place and stiffening it, I
30 provide braces 6, which are bolted to the web
of the angle-iron and thence extend at an an-
gle to the pole, where they are secured by a
single bolt 7. The horizontal flange of the
35 bar is perforated for the insertion of the insu-
lator stems 8, which are provided with enlarge-
ments resting upon the upper face and are
secured by nuts engaging their lower screw-
threaded ends.

The face of the pole immediately beneath
40 the slot is preferably squared off to afford a
better bearing for the web of the arm, as shown
at the lower portions of Figs. 1 and 2.

The advantages of my invention will be ap-
preciated by those skilled in the art. The
horizontal flange or leg of the angle fitting 45
in the slot gives the bar a secure hold upon
the pole and allows the use of a very light sec-
tion of the rolled angle. The angle iron may
be cheaply bought in the market and easily
50 cut up into sections of a suitable length and
perforated for the bolts and insulator stems,
and the life of the bar is much longer than
any of the ordinary wooden bars now used.

Many changes may be made in the form and
arrangement of the parts without departing 55
from my invention, since

What I claim as new, and desire to secure
by Letters Patent, is—

1. The combination with a telegraph pole
having a narrow horizontal slot, of an angle 60
iron cross-bar having its flange fitting snugly
within the slot and its web extending in a ver-
tical direction exterior to the slot, and secur-
ing devices arranged to hold the cross-bar in
place; substantially as described. 65

2. The combination with a telegraph pole
having a narrow horizontal slot, of an angle iron
cross bar having its flange fitting snugly
within the slot and its web extending in a ver-
tical direction exterior to the slot, and braces 70
extending from the cross-bar to the pole; sub-
stantially as described.

3. The combination with a telegraph pole
having a deep horizontal slot and a wide shal-
low recess, of an angle-iron having its flange 75
within the horizontal slot and its web fitting
in the recess; substantially as described.

In testimony whereof I have hereunto set
my hand.

JAMES B. OLIVER.
